ESCAPEMENT MECHANISM FOR TYPE-WRITERS, &c.

1,145,832.

Specification of Letters Patent. Patented July 6, 1915.

Application filed January 10, 1911. Serial No. 601,820.

To all whom it may concern:

Be it known that I, GEORGE W. DONNING, a citizen of the United States, residing at Stamford, in the county of Fairfield and 5 State of Connecticut, have invented certain new and useful Improvements in Escape- 10 ment Mechanisms for Type-Writers, &c., of which the following is a specification, reference being had therein to the accompany- 15 ing drawing.

This invention relates to escapement mechanisms, and is applicable to typewriters, adding machines, etc.; in fact, it may be conveniently applied to many forms of ma- 15 chines wherein it is necessary to utilize mechanism for producing a step-by-step travel of a carriage or the like.

The mechanism contemplated by this invention is of an exceedingly simple design; 20 it has the characteristic of durability; its cost of production, by reason of the fact that it comprises comparatively few parts, is very low; and, furthermore, the results achieved by its employment, in the kind of machines 25 specified, make such machine a most effective one for the purposes designed. Its use enables the machine to be operated with great rapidity and ease, and the parts of the machine controlled thereby may be effectually 30 accelerated in their operation, whereby relative movement and coöperation of such parts is facilitated to preclude interference or collisions therebetween. The construction of the mechanism and the relative arrangement 35 of the parts thereof are such as to adapt the mechanism, by comparatively slight modification or variation, to any make of machine wherein an escapement has to be utilized.

An important object of the invention is to 40 utilize the power of the carriage-propelling spring, where such an element is employed, or to utilize the weight and force of the traveling carriage, to effect an acceleration 45 of the movements of the parts of the ma- chine whereby, as in a typewriter, the mo- 50 ment an impression has been made by the printing member, the parts utilized to actuate said printing member, or the like, may, through the action of my escapement mech- anism, be rapidly positioned out of the rec- 55 ognized interference-zone. The invention of course is adapted to be combined with any means other than those specified, the influ- 60 ence of which toward propelling or driving

or otherwise moving the carriage, is em- 55 ployed.

Another object is to secure a more rapid let-off or movement of the carriage; and this result is accomplished by employing means which are direct in their action and which 60 are so designed and arranged as to reduce friction to a minimum and which, moreover, are so constructed and arranged as to be capable of being disconnected or disengaged from the carriage-propelling power 65 before the movable or moving parts (the actuation of which has been accelerated) have been restored to their normal positions of rest.

Still another object of the invention is to 70 include, in such escapement-mechanism, means whereby the same may conveniently be adjusted to change the degree of spacing- movement of the carriage, and which means is controlled by a key disposed within and 75 as a part of the regular keyboard.

Another object is to provide means, pref- 80 erably operated by the carriage-release mech- anism, and adapted to lock the escapement- wheel and the limber or loose dog—both forming constituent elements of the escape- 85 ment-mechanism—against actuation while the carriage is released or rendered inopera- tive, and the provision of which means eliminates the possibility of a spacing movement 90 of the carriage while the parts of the mech- anism are being restored to normal position for action.

A further object is to construct and ar- 90 range the parts of the mechanism, whereby carriage-back-shifting (one or a plurality of spaces) may be effected without combin- 95 ing, with such mechanism, an additional de- vice for effecting this result; and, moreover, whereby the back shifting shall be variable, according to what the normal spacing of 100 the traveling member is set.

These several objects, and others which it is unnecessary to mention, are possible in my construction by reason of the fact that 100 the location of the axis of the dog-carrier, and the position of the operating dogs rela- tive to a line drawn through the center of the axis of both the escapement-wheel and the dog-carrier, are such that but little move- 105 ment of the engaging parts is required to engage and disengage them; and, as a result, a strong repulser or accelerated effect upon

the parts and devices controlled thereby is produced without employing the usual bevelled dog or rack.

With these and other objects in view, the invention resides in the novel construction and aggroupment of the parts, devices and mechanisms, as now to be specifically described.

In the accompanying drawings—in which I have illustrated one of several embodiments of my invention and from which it will be recognized that the invention is susceptible of a wide range of modification without departing from the spirit thereof—
 10 Figure 1 is a view in plan of a carriage-supporting frame or sustaining plate; with my improved escapement-mechanism applied thereto; Fig. 2 is a rear elevation of the structure; Fig. 3 is an end elevation thereof, looking from the left-hand side, and in which the parts constituting the carriage-release device are shown, in dotted lines, in the position they assume when actuated to release the carriage; Fig. 4 is a similar view, 20 looking from the right-hand side; Fig. 5 is an enlarged detached view of the escapement-wheel, and the dog-carrier arranged in juxtaposition thereto, and including the dogs and the parts which control their operation; Figs. 6, 7, 8 and 9 are views in detail, respectively, of the escapement-wheel and its support; the dog-carrier on which is formed the rigid dog; the limber dog; and the escapement-wheel locking device 30 which is adapted to engage with the escapement-wheel when the carriage-release mechanism is actuated; Figs. 10, 11 and 12 are diagrammatic views illustrating the successive operations of the mechanism during the depression of a key-lever connecting with the escapement-mechanism; Figs. 13 and 14 are similar views of the same during the return of the key-lever to normal position; Fig. 15 is a perspective view (with certain parts of the carriage-supporting frame omitted) of the variable-space-mechanism for controlling the degree of spacing movement; Figs. 16 and 17 are elevational views of the escapement-mechanism, showing the position of the parts during the operation of effecting back-shifting; and Fig. 17^a is a diagrammatic, elevational view illustrating the escapement-wheel and the dogs engageable therewith; Fig. 18 is a view in 50 sectional elevation of a modified form of carriage-release mechanism and adjunctive wheel-locking device.

In these drawings: The reference numeral 1 designates a frame-work or supporting plate, which may be that of a typewriter, or of an adding machine, or of any other form of machine to which an escapement-mechanism is applicable.

60 Mounted upon the frame are tracks or guides 2 adapted to be traversed by a car-

riage 3, the latter being provided with rollers 4 which engage said tracks or guides, and which carriage moves under the influence of any suitable motor or power device or element, such as a carriage spring 3^a. The carriage is also provided, as usual, with a rack 6 arranged parallel with said tracks or guides. Arranged in juxtaposition to said rack is my improved escapement-mechanism 7: This comprises an escapement-rack, in this instance, shown in the form of a wheel 8, fast on one end of a stub-shaft 9 suitably journaled in a supporting yoke or trunnion member 10 mounted upon the supporting frame 1. Upon the end of the stub shaft opposite to the escapement-wheel, is a pinion 9^a which is adapted to mesh with the rack aforementioned.

Carriage-release mechanism.—Upstanding from the said trunnion member 10 is a bracket 11, upon which is pivoted a wheel-engaging pawl 12 held out of engagement with the escapement-wheel by a spring 13. As shown, this pawl is pivoted intermediate of its ends; one end is adapted to engage the escapement-wheel, while the other end overlies the upper portion of the rack. It may now be stated that this rack is mounted upon arms 14, 14, which are fast upon a spring-controlled rock-shaft or spindle 15, suitably journaled in the carriage, and to which is attached a key-member 17, whereby the spindle may be rocked to elevate the rack, which movement rocks said pawl into engagement with the escapement-wheel, for a purpose presently to be explained.

Dog mechanism.—Depending from said yoke member is a lug or extension 18 upon which is pivoted a dog-carrier 19. As will be observed, the pivotal point or axis of the dog-carrier is disposed eccentrically in relation to the boundaries of the carrier and, moreover, is in approximately vertical alignment with the axis of the escapement-wheel—the specified relative position of the axis being for purposes presently to be explained. Formed integral with, or suitably mounted upon, the dog-carrier, at the upper left-hand corner, is a rigid or holding dog 20 adapted to alternately engage the escapement-wheel. The dog-carrier is provided, adjacent to its axis, with a groove or channel 21 extending obliquely to a line drawn through the axes of the dog-carrier and the escapement-wheel. Slidably disposed in said groove 21 is a limber or loose-dog-carrying member 22 of length greater than the height of the rigid dog-carrier, whereby both ends project beyond the edges thereof. At the upper end of the member 22 is a dog 23, which will hereinafter be designated the loose dog or the limber dog. The opposite end of the member 22 is provided with a stud or lug 24 to which one end of a retractile spring 25 is connected, the opposite

end of which is attached to a stud 26 mounted in or on the supporting plate 1. Overlying the dog-member 22 are lugs or extensions 27 projecting from a plate 28 suitably secured to the lower portion of the dog-carrier 22. As will be seen, the position of the loose dog 23 is such that it will alternate with the rigid or holding dog 20 to engage the escapement-wheel, and that, by these, the control of the carriage, under the action of the carriage spring, is accurately effected. Moreover, the loose dog member 22, under the action of the spring 25, when it is disengaged from the escapement-wheel, is actuated upwardly in a direction oblique to a line which would cut the axes of the escapement-wheel and dog-carrier 19. Furthermore, the operative faces 20^a of the rigid dog 20 and 23^a of the loose dog 23, are such as to have a different form of engagement with the escapement-wheel, all as will be more particularly pointed out hereinafter, and at which time, also, it will be explained how the carrier 22 is adapted to position the dogs 20 and 23 alternately in engagement with the escapement-wheel, how the spring 25 aids in controlling the position of the carrier 22, and how the timing of the alternate engagement of the dogs is effected whereby the greatest rapidity of actuation of the parts may be produced. For the present, it will suffice to say that the positioning, and the controlling of the positions, of the parts, are positive and under the control of the operator at all times.

The spring 25 performs a dual function, in that it actuates the loose dog member after the loose dog is disengaged from the escapement-wheel; and, secondly, it assists in holding the dog-carrier 19 in normal position after the rigid dog has been disengaged from the escapement-wheel. This latter function is due to the fact that its point of attachment to the dog-carrier, relative to the axis thereof, is such that, being constantly under tension, it tends to pull upwardly upon the carrier to maintain the loose dog in holding engagement with the escapement-wheel and the rigid dog out of engagement therewith.

Attached to the dog-carrying member 19, as by the slot-and-pin connection 29, is a two-part link 30, one part of which is preferably threaded into the other, as shown. This form of connection permits the link structure to be lengthened or shortened, whereby proper adjustment may be conveniently effected. Pivotal connecting with the lower end of the link 30 is an actuating arm 31 fulcrumed at its opposite end upon a bracket or post 32 suitably attached to the frame-work of the machine. Pivotal attached to the arm 31, intermediate of its ends, is a short link 33 which, at its lower end, connects with and is operated by a uni-

versal bar 34 extending transversely of the machine and operative by a plurality of key-levers 35 preferably fulcrumed at their rear ends, in the usual way. These key-levers are preferably engaged by brake-springs 36. It will be seen that the depression of any of these key-levers, will actuate the universal bar, and that this, in turn, will operate the actuating arm 31, link 30, and dog-carrier 19.

Variable spacing.—Nowadays, it is desirable to provide means whereby the spacing movement of the carriage may be varied at the will of the operator. Therefore, in my improvement, I have included mechanism for controlling the movement of the dog-carrier or other movable part, whereby the degree of movement thereof may be changed to increase the step-by-step movement of the carriage: I will now described this variable spacing mechanism: Extending transversely of the machine, and preferably journaled in uprights 1^a, which may also be utilized for sustaining the supporting plate 1, is a rock-shaft 37, on one end of which is fixed a forwardly-extending arm 38, to which is jointed a link 39 connecting, at its lower end, to a controlling lever 40, fulcrumed at its rear end in any suitable manner, and extending forwardly into, and forming a part of, the keyboard 41 of the machine. This controlling-lever is maintained in position by a spring 42 which engages with it, and its upward movement is limited by a stud 43 disposed upon a suitable part of the frame-work of the machine and in the path of movement of the lever.

Upstanding from the base or other part of the frame-work of the machine is a bracket 44 provided with a guiding-slot 45 in which the controlling-lever 40 is adapted to move. Pivoted to said bracket, below the plane of the lever 40, is a latch or holding-member 46 provided with a lug 46^a adapted to engage the upper edge of the lever 40 when depressed. Mounted on the bracket, to the rear of the latch, is a stud 44^a which is designed to limit the outward movement of the latch 46.

Fast on the rock-shaft 37 is an upwardly extending abutment member 47 provided with an engaging lug or extension 47^a. Normally, the lug 47^a occupies a position in the path of the thrust or upward movement of the loose dog member 22. When, however, double-spacing of the carriage is desired, the operator depresses the controlling lever 40 and latches it by the member 44. The depressing movement of the lever 40 rocks the shaft, through the intermediate link 39 and arm 38, and thereby positions the member 47 out of the path of movement of the loose dog-member 22. When thus uncontrolled, the tendency of the dog-member 22 is to move upwardly under the action of the spring 25. This movement of the dog, how-

ever, for the variable spacing, is controlled by the stud 24 to which said spring 25 is attached. By enlarging the body-portion of the abutment-member 47 and providing the 5 active engaging side thereof with steps—one or another of which would be engaged by the dog (according to the character of spacing that the carriage is set to space)—the stud 24 need not be relied upon to control 10 the thrust of the dog. The return movement of the dog member 22 is effected by the rotative movement of the escapement-wheel which movement, as will well be understood, is effected by the travel of the carriage 15 under the action of the carriage spring 3^a. To limit the movement of the dog member 22, in returning to normal position, it is provided with one or more shoulders 22^a adjacent to its upper end, and which shoulders 20 are adapted to abut against the edge 19^a of the dog carrier 19.

Carriage-back-shifting.—The construction and relative arrangement of the parts of this escapement-mechanism is such that back-shifting of the carriage is permitted, and the extent of back-shifting is determined by the position of the abutment member 47; that is to say, if it is in the path of movement of the dog member 22, the back-shifting will be 25 only for a single space; whereas, if said abutment member 47 has been positioned out of the path of the dog member 22, the spacing movement will be doubled. In other words, the back-shifting will be according 30 to the character of spacing for which the carriage has been fixed to travel, and which, as aforesaid, is governed by the control lever 40. If the operator desires to back-shift the carriage when fixed for single-spacing, she 40 will manually push the carriage toward the starting position. This will rotate the escapement-wheel in the direction opposite to its normal rotation. As it is the loose dog which is in engagement with the escapement-wheel after each spacing movement of the carriage, the reverse rotation of the escapement-wheel will draw the loose dog upwardly and into engagement with the abutment member or single-space stop 47, and 45 this will limit the further backward movement of the carriage. Simultaneously, the escapement-wheel will, by reason of its sliding engagement with the loose dog, rock the member 22 and effect an engagement of the loose dog 23 into engagement with it, whereby 50 overthrow rotative movement of the escapement-wheel is prevented and the carriage positively stopped at a position corresponding exactly with that from which the 55 carriage had been spaced by the previous actuation of a key-lever. As will be clear, the rearward movement thus permitted will correspond to the normal forward spacing movement permitted by the escapement- 60 mechanism, as already described. If, how- 65

ever, the machine is set for double-spacing, and the single-space stop or abutment member 47 is positioned out of the path of movement of the dog member 22, the reverse rotative movement of the escapement-wheel 70 will draw the dog member 22 upwardly and beyond the normal engaging position of the single space stop 47 and, in fact, until the stud or pin 26, carried by the dog member 22, engages the lower extension 27 of the 75 plate 28. The escapement-wheel will, then, force the loose dog 23 out of holding engagement with it and, thereby rock the dog carrier 22 on its axis so as to force the rigid dog 20 into operative engagement with the 80 escapement-wheel and which will, then, prevent further rotative movement of the escapement-wheel. The rigid dog 20, therefore, becomes an abutment to limit the further backward movement of the carriage 85 which, thus, has now been positioned two spaces backwardly toward the starting position and, in consequence, in a position to permit printing in the space from which the carriage had been moved by the last actuation of one of the keys, and which, as will be understood, equals a distance of two spaces. It will now, also, be clear that, whenever the operator desires to release the carriage so as to position it at any required point or to return it to starting position, she effects a raising of the rack—through the instrumentalities already described—to rock the pawl 12 into engagement with the escapement-wheel. Thereby, 90 the rack is simultaneously disengaged from the pinion 9^a, so that no actuation thereof can occur, and the pawl locks the escapement-wheel and, in consequence, all of the other elements of the escapement-mechanism 95 against accidental movement. I have, thereby, provided means which are operated, by the carriage-release mechanism, to lock the escapement-wheel and loose-dog against movement while the carriage is released, and 100 in this way prevent the movement of the carriage one space while the parts are being restored to position. When the operator releases her touch upon the key-lever and the rack is permitted to return to normal position and into engagement with the pinion, the pawl, under the action of the controlling spring connected therewith, disengages from the escapement-wheel and thereby permits 105 the same to be actuated when any of the key-levers are depressed by the operator. 110

In Fig. 18, I have shown a somewhat different form of carriage-release mechanism: In this instance, the pinion 9^a is controlled by a clutch-device 48 held normally in engagement with said pinion by a spring 49 and adapted to be disengaged therefrom by a bell-crank-lever 50, which may be actuated through a link 51, by a key-member (not shown) disposed in or contiguous to 115 120 125 130

the keyboard. It will be seen that the lever 50 has an angulated extension 50^a which is adapted to lockingly engage the escapement-wheel 8 when the lever 50 is rocked to un-clutch the parts.

5 The simplicity of the construction, the direct action incident to the actuation of the operable parts, and the peculiar relative arrangement thereof, combine to produce an escapement-mechanism which is capable of 10 the highest degree of efficiency, whereby certain of the parts are so controlled that their actuation is accomplished with an accelerated effect. Moreover, by relying upon 15 the carriage spring in some instances, or, in others, upon the weight of, and the momentum to, the carriage, I thereby use instrumentalities to accelerate the movement of the parts of the machine so that, the instant 20 an impression has been made by a type-bar which has been actuated to the printing position by its respective key-lever, all parts which are movable into a zone of interference therewith are rapidly removed 25 from that zone. In fact, it is the desideratum and important feature of my invention to expedite and accelerate the removal of any and all operative parts from the field or zone of interference before another part 30 or set of parts is moved into that field or zone and to permit a rapid let-off of the carriage the instant a printing-character is printed upon the work-sheet. Another important feature is that, in the event that the 35 carriage is sluggish in its movement, for any reason, the inactive face of the holding dog will, when the key-lever is being depressed by the operator, co-operate with the inactive face of one of the teeth of the escapement-wheel 40 and cam the carriage forward to the next letter-space in time to permit the proper imprinting of the desired printing-character upon the work-sheet. To this end, the parts are so formed and arranged that all 45 friction is eliminated or reduced to a minimum and, at the same time, a leverage upon the operating parts is effected to facilitate their restoration to normal position: For this purpose, as will be noted, the fulcrum 50 or axis of the dog-carrier 19 and the position of the rigid and loose dogs are such, relative to a line drawn through the center of the axis of the dog-carrier and of the escapement-wheel, that but little movement of 55 these parts is requisite to engage and disengage them; and, incidentally, there is produced an exceedingly strong repulser or accelerated effect upon the parts without the employment of a beveled dog or a beveled 60 rack, as now customary.

The particular relative position of the axis or fulcrum of the dog-carrier 19 is exceedingly important; and the efficiency of my device resides, in a large measure, in this 65 feature: It is to be seen that the nearer to

the escapement-wheel the axis of dog-carrier is (as indicated diagrammatically by A, Fig. 17^a), the less will be the force of the repulse, even with the holding-dog formed and positioned as it now is shown. 70 On the other hand, (as indicated diagrammatically by B and C, Fig. 17^a) the more remote is the fulcrum or axis of the carrier (within limits, of course) the greater will be the repulse. Practical operation of the 75 device has shown that, for general purposes, the preferable relative position of said axis is substantially as herein disclosed. By accelerating and augmenting the spacing movement of the carriage, due to the employment of the specified means which include direct connections and direct action incident to their relative arrangement and construction, the parts are accelerated in 80 their movement toward normal position. 85

As I am aware that it has heretofore been proposed to provide for the rapid let-off of the carriage and, also, to utilize, as a repulser, the carriage-spring, operating in conjunction with beveled or cammed toothed members, I do not claim these features *per se*; but, by the use of my device, I provide an escapement-mechanism which is more rapid in its operation than those now in use; and, as has been found in the practical operation of my device, the "letting off" of the carriage, as the dogs disengage from the escapement-wheel, is exceedingly rapid; and, besides, it has also been found that the carriage starts in its movement sooner and more rapidly than where the engaging parts are beveled and arranged at right angles. Moreover, the particular construction of the same produces a most practical and powerful accelerator for restoring the key-operated or other actuated parts to normal position; and by which mechanism I eliminate practically all friction, whereby the number and strength of individual springs for the operative parts are greatly reduced, and, 100 in some instances, entirely eliminated, and, especially, because I am not, by my construction, obliged to rely upon beveled dogs or beveled racks. On the contrary, the escapement-dogs operate in relation to the escapement-wheel in such manner that their engagement and disengagement is facilitated without engendering appreciable friction and, for this reason, the requirement of a strong carriage-spring is rendered unnecessary: It will be noted, for instance, that the loose or limber dog 23, when it actuates, after disengaging from the teeth of the escapement-wheel, is projected past these teeth in a line which is relatively straight in reference to the plane of the two proximate teeth from between which it has been removed. Were the body of this dog curved in the direction of and to conform to the teeth, there would be engendered much friction, in con- 115 120 125 130

sequence of which a stronger spring to control the same would necessarily have to be employed. Therefore, the operating face of this dog is cut on a radius relatively to the 5 axis of the dog-carrier 19. It will therefore be observed that the active face of the tooth of the escapement-wheel then adjacent to the loose dog is relatively straight and flat and that it is in radial line with respect to the 10 axis of the escapement-wheel; and, furthermore, that the outer periphery or active face of the loose dog is cut as practically a true arc relatively to the axis of the dog-carrier so that, when said dog is disengaging 15 from the tooth of the escapement-wheel, its movement is in a true arc relative to the face of said tooth. Again, it will be observed that the active face of the holding dog is so cut and positioned with relation to 20 the axis of the carrier that it will positively engage the active face of the adjacent tooth of the escapement-wheel simultaneously, approximately, with the disengagement of the loose dog from the tooth with which it has 25 been in contact, and that thereby any rotation of the escapement-wheel—and consequently any movement of the carriage—is prevented while the key-lever is held depressed by the operator's finger. Moreover, 30 the operative face of the rigid dog is made to conform to the surface of the loose dog. While I secure a repulser effect by the peculiar conformation of these parts relatively to each other, and also by reason of their 35 relative position and operation, I introduce a simple and more effective principle into the operation of escapement-mechanisms than has heretofore been proposed; and I therefore avoid the use of beveled or cam- 40 ed constructions, such as beveled dogs, beveled racks, and the like.

Repulser operation.—It will be seen that the loose or limber dog, which constitutes a detent-member, normally controls the es- 45 capement-wheel; that is to say, it is the dog which is in engagement with the escapement-wheel when the carriage comes to rest after each actuation of an operating key-lever. The actuation of the dog-carrier 19, 50 as by a key-lever, rocks the dog-carrier on its fulcrum, which operation effects a withdrawal of the loose-dog, by a slidingly-engaging movement, from the lower face of the tooth of the escapement-wheel with 55 which said dog normally engages. Simultaneously, said dog-carrier 19 is acting to position the rigid dog into engagement with the upper face of a tooth of the es- 60 capement-wheel, so that, just before the loose dog separates from the escapement-wheel tooth, the rigid or holding-dog will have engaged the proper tooth of the escapement-wheel. The instant that the loose dog is 65 free from the escapement-wheel, the spring 25 thrusts the dog-member 22 upwardly un-

til it engages the spacing stop-member or abutment 47, where the machine has been set for normal spacing; or, if the machine has been set for double-spacing, the dog-carrier 22 will have been actuated beyond the engaging position of the member 47 and until the stud 26 engages the lowermost of the two of the lugs or extensions on the plate 28. Of course, the moment that the loose dog disengages from the escapement-wheel, the carriage spring or carriage motor—in whatever form it may be—acting upon the carriage tends to rotate the escapement-wheel and, by this action, to displace therefrom, by a rotative movement, the rigid or holding dog. The dog member 19, being under no restraint and aided by the spring 25, is given an impulse. This impulse, by reason of the form of the engaging faces of the teeth of the escapement-wheel and of the holding dog, is transmitted by the dog carrier to the parts and devices connecting therewith which, in the first instance, have operated to actuate the dog carrier and thereby rock the dog carrier in a direction 70 opposite to that of the impulse-producing direction, and which rocking movement has disengaged the loose dog from the escapement-wheel, as already described. The impulse, thus imparted to the parts, as just 75 mentioned, restores them to normal position, and is of a character—by reason of the direct connection of the parts, the particular nature of the engagement of the holding dog with the escapement-wheel, etc.—that it 80 facilitates and expedites such restoration of the parts. As a result, any elements or devices, which have to be actuated into a zone where they are in danger of colliding with 85 elements or devices being returned to normal position, are instantly and rapidly removed from that zone and to normal position before any of the other elements or devices are again actuated thereinto.

The impulse-producing action, just de- 90 scribed, results from the fact that the es- 95 capement-wheel repels the holding dog and, thus, the dog carrier, from engagement with it. Referring to Fig. 12, for example, it will be noted that when the dog 20 is in engagement with a tooth of the escapement-wheel, the engaging face of this dog—which is a straight face—lies in contact throughout its length with the face of the escapement-tooth which is also a straight face. This action—that is, the impulse imparted to the dog carrier, in the manner and for the reasons specified—is utilized for at least two purposes, namely, (1) to rock the dog carrier on its fulcrum and, thereby, effect 100 an engagement of the detent dog with the escapement-wheel; and (2) to operate the parts which initially actuate the dog carrier and, thus, restore them to normal position. Therefore, I have herein, in some in- 105 110 115 120 125 130

stances, referred to this operation as a "re-pulser action".

It will be understood, from the foregoing description, that my invention is applicable 5 to various forms of structures wherein is employed a carriage that acts under the control of a step-by-step mechanism. I have designed this escapement-mechanism for use in typewriters of various types, including of course the so-called round platen and flat 10 platen or billing machine, book-typewriters and the like; and, also, in adding machines, in various forms of computing machines, etc. Likewise, the invention is equally applicable to so-called book-typewriters for 15 controlling the movement of the book-supporting structures forming a part of this class of machines.

While I have herein described my invention in detail, and illustrated the same in 20 but one form or embodiment, it is nevertheless to be understood that it is susceptible of a wide range of modification without departing from the spirit of the invention; and it is also to be understood that notwithstanding the fact that I have described the 25 details of the structure, I do not limit myself to such details except in so far as the same are specifically included in the claims.

Having thus fully described my invention, 30 its construction, its mode of operation, and the several uses thereof, what I claim as new and desire to secure by Letters-Patent is:

1. An escapement mechanism comprising 35 an escapement member having the engaging faces of its teeth cut on lines radiating approximately from its center, a motor for actuating said member, and a plurality of dog members lying and moving in the plane of 40 the member and adapted to be alternately actuated into coöoperative engagement therewith so that when one of said dog members is in its holding position substantially its entire working face is in engagement with 45 one of the teeth of said escapement member and has a relatively prolonged sliding movement thereon, whereby said motor tends to return said parts to normal position.

2. An escapement mechanism comprising 50 an escapement member having the engaging faces of its teeth cut on lines radiating approximately from its center, a motor for actuating said member, a plurality of dog members lying and moving in the plane of 55 the member, and a dog carrier common to said dog members and operable to effect engagement thereof with said escapement member so that when one of said dog members is in its holding position its working 60 face has a sliding engagement of substantial duration with one of the teeth of said escapement member, whereby said motor tends to return said parts to normal position.

65 3. An escapement mechanism comprising

an escapement member having the engaging faces of its teeth cut on lines radiating approximately from its center, a motor for actuating said member, a plurality of dog members lying and moving in the plane of 70 the member, a dog carrier common to said dog-members and operable to effect engagement thereof with said escapement member so that when one of said dog members is in its holding position its working face has a 75 sliding engagement of substantial duration with a tooth of said escapement member, whereby said motor tends to return said parts to normal position, and actuating mechanism for said carrier. 80

4. An escapement mechanism comprising an escapement wheel having the engaging faces of its teeth cut on lines radiating approximately from its center, a plurality of dog members lying and moving in the plane 85 of the member, a dog carrier common thereto and operable to effect engagement of said dog members with said escapement wheel, and actuating means including a carriage-moving motor for facilitating movement of 90 the escapement wheel, the engagement of the dog member with said wheel being such that when the former is in a holding position against the latter the working face of the dog member has a sliding engagement of 95 substantial duration with a tooth of the wheel, whereby said motor tends to return said parts to normal position.

5. An escapement mechanism comprising 100 an escapement wheel having the engaging faces of its teeth cut on lines radiating approximately from its center, a motor for actuating said wheel, a plurality of dog members lying and moving in the plane of 105 the wheel, a spring-controlled dog carrier common thereto and operable to effect engagement of the dog members with the escapement wheel, and actuating means therefor, the engagement of the dog member with said wheel being such that when the former 110 is in a holding position against the latter the working face of the dog member has a sliding engagement of substantial duration with a tooth of the wheel, whereby said motor tends to return said parts to normal position. 115

6. An escapement mechanism, comprising 120 an escapement wheel, a motor for actuating said wheel, a dog carrier juxtaposed thereto, a holding dog carried thereby, and a detent dog slidably mounted on said carrier and alternating with said holding dog in engaging said escapement wheel, both of said dogs lying and moving in the plane of the wheel, the operative or engaging face or portion of 125 one of said dogs being cut straight relatively to its path of movement toward and away from the axis of said escapement-wheel, the engagement of one of said dogs with said wheel being such that when the former is in 130

a holding position against the latter substantially the entire working face of the dog is in engagement with a tooth of the wheel, whereby said motor tends to return said parts to normal position.

7. An escapement mechanism, comprising an escapement wheel having the engaging faces of its teeth cut on lines radiating approximately from its center, a carriage, a rack-and-pinion connection between said carriage and escapement wheel, a carriage-propelling motor connecting with said carriage and adapted to actuate the wheel, a dog carrier disposed in juxtaposition to said escapement wheel, a holding dog on said carrier and movable thereby into and out of engagement with said wheel, a loose dog movably mounted on said carrier and positioned thereby into engagement with said wheel, both of said dogs lying and moving in the plane of the wheel, actuating means for said carrier, the engagement of one of said dogs with said wheel being such that when the former is in a holding position against the latter substantially the entire working face of the dog is in engagement with a tooth of the wheel, whereby said motor tends to return said parts to normal position, and means connecting with said carrier and adapted to be actuated thereby.

8. An escapement mechanism, comprising an escapement wheel having the engaging faces of its teeth cut on lines radiating approximately from its center, a carriage, a rack-and-pinion connection between said carriage and escapement wheel, a carriage-propelling motor connecting with said carriage, a dog carrier disposed in juxtaposition to said escapement wheel, a holding dog on said carrier and movable thereby into and out of engagement with said wheel, both of said dogs lying and moving in the plane of the wheel, actuating means for said carrier, means for controlling the actuation of said carrier in at least one direction, the engagement of one of said dogs with said wheel being such that when the former is in a holding position against the latter substantially the entire working face of the dog is in engagement with a tooth of the wheel, whereby said motor tends to return said parts to normal position, and means connecting with said carrier and adapted to be actuated thereby.

9. An escapement mechanism, including in combination, an escapement wheel having the engaging faces of its teeth cut on lines radiating approximately from its center, a carriage, a rack-and-pinion connection between said carriage and escapement wheel, a carriage-propelling motor connecting with said carriage, a dog carrier disposed in juxtaposition to said escapement

wheel, a holding dog on said carrier and movable thereby into and out of engagement with said wheel, a loose dog movably mounted on said carrier and adapted to be positioned thereby into engagement with said wheel, and actuating means for said carrier, one of said dogs having such engagement with said wheel that when it is in its holding position thereagainst substantially its entire working face is in contact with a tooth of the wheel, whereby said motor tends to return said parts to normal position when said holding dog is moved out of engagement with said escapement wheel and said carrier is operated to influence the actuation of said actuating means.

10. An escapement mechanism, comprising an escapement wheel, a carriage, a rack-and-pinion connection between said carriage and escapement wheel, a carriage-propelling spring connecting with said carriage, a dog carrier disposed in juxtaposition to said escapement wheel and having its axis substantially parallel to the axis of said escapement wheel, a holding dog on said carrier and movable thereby into and out of engagement with said wheel, and a loose dog movably mounted on said carrier and positioned thereby into engagement with said wheel, one of said dogs having such engagement with said wheel that when it is in its holding position thereagainst substantially its entire working face is in contact with a tooth of the wheel, whereby said spring tends to return said parts to normal position.

11. An escapement mechanism, comprising an escapement wheel, a carriage, a connection between said carriage and escapement wheel, a carriage-propelling spring connecting with said carriage, a dog carrier disposed in juxtaposition to said escapement wheel, a holding dog on said carrier and movable thereby into and out of engagement with said wheel, a loose dog movably mounted on said carrier and positioned thereby into engagement with said wheel, actuating means for said carrier, one of said dogs having such engagement with said wheel that when it is in its holding position thereagainst substantially its entire working face is in contact with a tooth of the wheel, whereby said spring tends to return said parts to normal position, and a space-controlling device movable into and out of operative relation to said dog carrier to control the degree of travel of said carriage.

12. An escapement mechanism, comprising an escapement wheel, a carriage, a connection between said carriage and escapement wheel, a carriage-propelling spring connecting with said carriage, a dog carrier disposed in juxtaposition to said escapement wheel, a holding dog on said carrier and movable thereby into and out of engagement with said wheel, a loose dog movably mount-

- ed on said carrier and positioned thereby into engagement with said wheel, actuating means for said carrier, and variable spacing mechanism including a movable stop device 5 for controlling the degree of travel of said carriage, said carriage being shiftable in a direction reverse to its normal travel and adapted to be controlled in such shifting by said variable spacing mechanism.
- 10 13. An escapement mechanism, comprising an escapement wheel, a carriage, a connection between said carriage and escapement wheel, a carriage propelling spring connecting with said carriage, a dog carrier disposed in juxtaposition to said escapement wheel, a holding dog on said carrier and movable thereby into and out of engagement with said wheel, a loose dog movably mounted on said carrier and positioned thereby 15 into engagement with said wheel, actuating means for said carrier, one of said dogs having such engagement with said wheel that when it is in its holding position thereagainst substantially its entire working face 20 is in contact with a tooth of the wheel, whereby said spring tends to return said parts to normal position, carriage-releasing mechanism, and retaining means for controlling said escapement wheel while said 25 carriage is under the control of said carriage release mechanism.
14. An escapement mechanism, comprising an escapement wheel, a carriage, a connection between said carriage and escapement wheel, a carriage propelling spring connecting with 30 said carriage, a dog carrier disposed in juxtaposition to said escapement wheel, a holding dog on said carrier and movable thereby into and out of engagement with said wheel, 35 a loose dog movably mounted on said carrier and positioned thereby into engagement with said wheel, actuating means for said carrier, one of said dogs having such engagement with said wheel that when it is in its holding 40 position thereagainst substantially its entire working face is in contact with a tooth of the wheel, whereby said spring tends to return said parts to normal position, and a wheel locking device for controlling said 45 escapement wheel whenever said carriage is placed out of holding connection with said wheel.
15. An escapement mechanism comprising an escapement member having engaging 50 faces of its teeth cut on lines radiating from its center, a motor for actuating said member, dogs coöperating therewith and one of which has a relatively straight face, both of said dogs lying and moving in the plane 55 of the wheel, one of the dogs having such coöperative engagement with a tooth of said escapement member that when it is in its holding position thereagainst its working face has a sliding contact of substantial 60 duration with said tooth and receives there- 65 from an effective impulse as said member is moved under the influence of said motor, and an operating device operatively connected with the dogs for effecting their operation and adapted to be actuated under 70 the action of said impulse.
16. An escapement mechanism comprising an escapement member, a motor for actuating said member, engaging dogs coöperating therewith and one of which has a relatively 75 straight engaging face, both of the dogs lying and moving in the plane of the member, one of said dogs having such coöperative engagement with a tooth of said escapement member that when it is in its holding position thereagainst substantially its entire 80 working face is in contact with said tooth and receives therefrom an impulse as said wheel revolves under the influence of said motor, and actuating mechanism connecting with said dog and having imparted to it the impulse received from said dog.
17. An escapement mechanism comprising an escapement wheel, a power device operatively connecting therewith, engaging dogs 85 coöperating therewith and one of which has a relatively straight engaging face, both of said dogs lying and moving in the plane of the wheel, one of said dogs having such coöperative engagement with a tooth of said 90 escapement member that when it is in its holding position thereagainst substantially its entire working face is in contact with said tooth and receives therefrom an impulse-action whereby said power device tends 95 to return the parts to normal position, and actuating mechanism to which said impulse-action is transmitted.
18. An escapement mechanism comprising an escapement wheel having the engaging 100 faces of its teeth cut on lines radiating approximately from the center of said escapement wheel, a spring for said wheel, a plurality of wheel-engaging dogs, one of which has its operative face formed to correspond 105 with said wheel teeth, and a dog carrier, one of said dogs having such engagement with said wheel that when it is in its holding position thereagainst substantially its entire working face is in contact with a tooth of 110 the wheel, whereby said spring tends to return said parts to normal position.
19. An escapement mechanism comprising an escapement wheel having the engaging 115 faces of its teeth cut on lines radiating approximately from the center of said escapement wheel, a power device for said wheel, a plurality of wheel-engaging dogs, one of which has its operative face formed to correspond 120 with said wheel teeth, and a pivoted dog carrier, one of said dogs having such coöperative engagement with a tooth of said escapement member that when it is in its holding position thereagainst substantially its entire working face is in contact with said 125 130

tooth whereby rotation of said wheel under the influence of said power device will impart an effective impulse to said dog and its carrier and return the parts to normal position.

5 tion.

20. An escapement mechanism comprising an escapement wheel having the engaging faces of its teeth cut on lines radiating approximately from the center of said escapement wheel, a power device for said wheel, a plurality of wheel-engaging dogs, one of which has its operative face formed to correspond with those of the teeth of the wheel, and a movable dog carrier having its fulcrum disposed out of alinement with said dogs and parallel to the axis of said wheel, one of said dogs having such coöperative engagement with a tooth of said escapement member that when it is in its holding position thereagainst substantially its entire working face is in contact with said tooth whereby said wheel, when driven under the influence of said power device, will impart an effective impulse to said dog carrier.

25 21. An escapement mechanism comprising an escapement wheel having the engaging faces of its teeth cut on lines radiating approximately from the center of said escapement wheel, a power device for said wheel, a plurality of wheel-engaging dogs having their engaging faces formed slidingly to engage with those of the teeth of the wheel, a movable dog carrier having its fulcrum disposed out of alinement with said dogs and the axis of said wheel, one of said dogs having such coöperating engagement with a tooth of said escapement wheel that when it is in its holding position thereagainst substantially its entire working face is in contact with said tooth whereby said wheel, when driven under the influence of said power device, will impart an impulse to said dog carrier, and a variable spacing mechanism for governing the extent of rotative movement of said escapement wheel.

22. An escapement mechanism comprising an escapement wheel having the engaging faces of its teeth cut on lines radiating approximately from the center of said escapement wheel, a power device for said wheel, a plurality of wheel-engaging dogs having their engaging faces formed slidingly to engage with those of the teeth of the wheel, a movable dog carrier having its fulcrum disposed out of alinement with said dogs and the axis of said wheel, one of said dogs having such co-operative engagement with a tooth of said escapement wheel that when it is in its holding position thereagainst substantially its entire working face is in contact with said tooth whereby said wheel, when driven under the influence of said power device, will impart an impulse to said dog carriage, a keyboard including key members for actuating said dog carrier, and

a variable spacing mechanism controlled at said keyboard for determining the degree of rotative movement of said escapement wheel.

23. An escapement mechanism comprising 70
an escapement wheel having the engaging
faces of its teeth cut on lines radiating approxi-
mately from the center of said escape-
ment wheel, a power device for said wheel, a
plurality of wheel-engaging dogs having 75
their engaging faces formed slidingly to en-
gage with those of the teeth of the wheel,
a movable dog carrier having its fulcrum
disposed out of alinement with said dogs
and the axis of said wheel, one of said dogs 80
having such coöperative engagement with a
tooth of said escapement wheel that when it
is in its holding position thereagainst sub-
stantially its entire working face is in contact
with said tooth whereby said wheel, 85
when driven under the influence of said
power device, will impart an impulse to said
dog carrier, and an escapement wheel locking
device juxtaposed to and movable into
engagement with said wheel. 90

24. An escapement mechanism comprising an escapement wheel, a motor for actuating said wheel, and detent and holding dogs coöperating with said wheel, one of said dogs having such engagement with said wheel that when it is in its holding position thereagainst substantially its entire working face is in contact with a tooth of the wheel, whereby said spring tends to return said parts to normal position, in combination with a carriage under the control of said escapement wheel, the normally inactive face of said detent dog also coöperating with said wheel to permit a limited back-shifting movement of said carriage. 95 100 105

25. An escapement mechanism comprising an escapement wheel, a motor for actuating said wheel, and detent and holding dogs coöoperating with said wheel, one of said dogs having such engagement with said wheel that when it is in its holding position thereagainst substantially its entire working face is in contact with a tooth of the wheel, whereby said spring tends to return said parts to normal position, in combination with a carriage under the control of said escapement wheel, the normally inactive faces of said detent and holding dogs also coöoperating with said wheel to permit a limited back-shifting movement of said carriage. 100 110 115 120

26. An escapement mechanism comprising an escapement wheel, and detent and holding dogs coöperating with said wheel, in combination with a carriage under the control of said escapement wheel, the normally inactive faces of said detent and holding dogs coöperating with said wheel to permit a limited back-shifting movement of said carriage, and a carriage-spacing regu- 125 130 135

lator coöperating with said carriage and shiftable in relation to one of said dogs to determine the degree of back-shifting of the carriage.

- 5 27. In combination, a carriage, a support therefor, a carriage motor device acting to propel said carriage in one direction, an escapement wheel connecting with said carriage and operating, in one direction, under 10 the influence of said carriage motor device, said wheel being provided with teeth cut on lines radiating approximately from its center, a movable dog-carrier juxtaposed to said escapement wheel, a holding dog carrier thereby and coöperating with a radiating tooth of said escapement wheel to control the same in its rotation in one direction, a detent dog also coöperating with said escapement wheel to control the rotation of 15 20 25 30 35 the same and connecting with and operated by said dog carrier, the said holding dog having a coöperative engagement with a tooth on said escapement wheel so that when it is in its holding position thereagainst substantially its entire working face is in contact with the tooth, said dog being releasable from said escapement wheel, when said detent dog engages therewith, to receive an impulse imparted to said escapement wheel under the influence of said carriage motor device, and actuating mechanism for said dog carrier operatively connecting therewith to receive the impulse imparted to said dog carrier and thereby to restore the parts of the actuating mechanism to normal position.

28. In combination, a carriage, a support therefor, a carriage motor device acting to propel said carriage in one direction, an escapement wheel connecting with said carriage and operating, in one direction, under the influence of said carriage motor device, a movable dog carrier juxtaposed to said escapement wheel, a holding dog carried thereby and engaging said escapement wheel to control the same in its rotation in one direction and having a coöperative engagement with a tooth on said escapement wheel so that when it is in its holding position thereagainst substantially its entire working face is in contact with the tooth, a detent dog carried by said dog carrier and having a sliding movement thereon at an angle to a line drawn through the axes of 55 the escapement wheel and dog carrier, means connecting with said detent dog to actuate it past one or more teeth of the escapement wheel, a guiding connection between said detent dog and said dog carrier 60 for guiding said detent dog into engagement with said escapement wheel, and actuating means connecting with said dog carrier and deriving movement therefrom under the influence of the impulse imparted thereto. 65 29. In an escapement mechanism, the

combination with a toothed wheel, of wheel-engaging dogs having movement independently of each other, one of said dogs having such engagement with said wheel that when it is in its holding position thereagainst substantially its entire working face is in contact with a tooth of the wheel, key-mechanism for controlling the same whereby the dogs are actuated to lock the escapement and the parts which it controls during 70 the downward movement of the key mechanism, and carriage-propelling mechanism acting upon the release of said wheel by said escapement positively to actuate the escapement mechanism and restore the 75 80 85 parts connecting therewith to their normal position.

30. An escapement mechanism, comprising a member provided with teeth having normally active and inactive faces, and dogs 85 also having normally active and inactive faces, one of said dogs having coöperative engagement with a tooth of said escapement wheel so that when it is in its holding position thereagainst substantially its entire 90 active face is in contact with the tooth of the wheel, in combination with a carriage under tension, and key-mechanism for actuating the dogs to permit advance movement of said carriage when said normally active 95 faces of the toothed member and dogs engage, and for positioning said normally inactive faces of the toothed member and one of the dogs in engagement to cam said carriage forward and accelerate its travel when 100 its normal travel is in any way retarded.

31. An escapement mechanism including in combination, a toothed member having straight operating faces, a pivoted dog carrier, and a dog thereon provided with an 105 operating face substantially similar to the operating faces of said toothed member, said dog operating as a detent when moved toward the axis of the toothed member and as an accelerator when moved in the opposite 110 direction.

32. An escapement mechanism including in combination, a toothed member provided with straight-cut teeth, a dog member arranged in juxtaposition thereto and carrying a dog 115 also provided with a straight-cut operative face, and means for producing a relative movement between said members so that the dog member will act as a detent when the movable member is operated in one direction relatively to the other member and as an accelerator when said movable member is actuated in the opposite direction.

33. An escapement mechanism including an escapement rack having teeth provided 125 with straight-cut working faces, a dog carrier arranged in juxtaposition thereto, a movable dog supported by said dog carrier, a dog-controlling member positionable into the path of movement of said dog carrier, 130

means for positioning said dog-controlling member in relation to the movable dog whereby the same will be permitted to have a variable movement, a second dog on the 5 dog carrier provided with a rack-engaging face which lies in a plane parallel with the working face of each of the teeth of said escapement rack when said dog is in engagement with said rack, and a motor act- 10 ing on said rack member to return the parts to normal position.

34. An escapement mechanism including in combination, an escapement rack provided with straight-cut teeth, a carriage 15 controlled thereby, a dog carrier arranged in juxtaposition to said rack, a movable dog supported on said dog carrier and provided with a straight-cut operative face, means for producing a relative movement between 20 the escapement-rack and the dog carrier so that the dog will act as a detent when the carrier is operated in one direction relatively to the rack and as an accelerator when said carrier is operated in the opposite di- 25 rection, coacting means carried by said dog and said carrier to permit a double-spacing movement of said carriage, and means positionable into the path of said dog and adapted to control its movement for a 30 single-spacing movement of said carriage irrespective of whether the dog is acting as a detent or as an accelerator.

35. An escapement mechanism including in combination, an escapement wheel pro- 35 vided with straight-cut teeth, a carriage controlled thereby, a dog carrier arranged in juxtaposition to said wheel, a movable dog supported on said dog carrier and provided with a straight-cut operative face, means 40 for producing a relative movement between the escapement-rack and the dog carrier so that the dog will act as a detent when the carrier is operated in one direction relatively to the rack and as an accelerator when said 45 carrier is operated in the opposite direction, coacting means carried by said dog and said carrier to permit a double-spacing movement of said carriage, and means positionable into the path of said dog and adapted to control its movement for a 50 single-spacing movement of said carriage irrespective of whether the dog is acting as a detent or as an accelerator.

36. An escapement mechanism including 55 in combination, an escapement rack pro- vided with straight-cut teeth, a carriage controlled thereby, a dog carrier arranged in juxtaposition to said rack, a movable dog supported on said dog carrier and provided 60 with a straight-cut operative face, means for producing a relative movement between the escapement-rack and the dog carrier so that the dog will act as a detent when the carrier is operated in one direction relatively 65 to the rack and as an accelerator when said

carrier is operated in the opposite direction, coacting means carried by said dog and said carrier to permit a double-spacing movement of said carriage, means positionable into the path of said dog and adapted to control its movement for a single-spacing move- 70 ment of said carriage, irrespective of whether the dog is acting as a detent or as an accelerator, and a key-lever for position- 75 ing said dog-controlling member.

37. An escapement mechanism including in combination, an escapement rack, a dog car- 80 rier arranged in juxtaposition thereto, a dog thereon adapted to coöperate with said rack and receive a repulse movement therefrom, a movable dog supported on said carrier, and a spring for actuating said dog into one or another of a plurality of operative posi- 85 tions and for actuating said dog carrier to augment the repulse movement imparted thereto.

38. An escapement mechanism including in combination, an escapement rack, a dog car- 90 rier mounted in juxtaposition thereto, a movable dog supported on said carrier, a car- riage controlled by said escapement mecha- 95 nism for a single or a plurality of spaces and adapted, when moved in a position opposite to its normal travel, to actuate said escape- ment rack and rock said dog carrier to po- sition said movable dog into engagement with one or another of the teeth of said es- capement rack, and means for controlling movement of said movable dog and, thus, of the back-shifting movement of said carriage. 100

39. An escapement mechanism, comprising a rack and two rack-engaging dogs formed, respectively, with relatively straight and arcuated active engaging faces, one of said dogs having such coöperative engagement 105 with a tooth of said rack that when it is moving in relation thereto it has a sliding engagement therewith of substantial dura- 110 tion and when it is in its holding position thereagainst substantially its entire working face is in contact with said tooth and re- ceives therefrom an impulse as said rack is moved.

40. An escapement mechanism, comprising a rack and two rack-engaging dogs formed, 115 respectively, with relatively straight and arcuated active engaging faces, one of said dogs having coöperative engagement with a tooth of said rack, the engaging face of said dog and the face of said rack tooth when 120 in contact having a sliding engagement of substantial duration whereby movement of the rack produces an impulse on the dog.

41. An escapement mechanism comprising an escapement rack; a motor therefor; a dog 125 carrier juxtaposed thereto; a holding dog car- ried thereby and having a relatively straight active face; and a detent dog movably mounted on said carrier and alternating with said holding dog to engage said rack and 130

5 having an arcuated active face; the contact of one of said dogs with the rack being such that it has a sliding engagement of substantial duration thereon, whereby said motor tends to return said parts to normal position.

10 42. An escapement mechanism comprising an escapement rack; a motor therefor; a dog carrier juxtaposed thereto; a holding dog carried thereby and having a relatively straight active face; and a detent dog mov-
15 ably mounted on said carrier and alternating with said holding dog to engage said rack and having an arcuated active face; the contact of one of said dogs with the rack being such that it has a sliding engagement of substantial duration thereon, whereby said motor tends to return said parts to normal position; the other dog likewise having a sliding engagement of substantial duration
20 with said rack to hold said rack against movement.

43. As escapement mechanism comprising a rack, a motor therefor; coöperating dogs

arranged in relation thereto and each having a plurality of rack-engaging portions, the 25 coöperation of one of said dogs with said rack being such that it has a sliding engagement of substantial duration thereon, whereby said motor tends to return said parts to normal position, in combination with a carriage under tension, and key-mechanism for actuating the dogs to position one of their engaging portions in contact with the rack and permit advance movement of said carriage and for actuating said dogs to position the other of their engaging portions in contact with the rack and thereby cam the carriage forward and accelerate its travel when its normal travel is in any way retarded.

30 In testimony whereof I affix my signature in presence of two witnesses.

35 GEORGE W. DONNING.

40 Witnesses:
